UNITED STATES PATENT OFFICE

114,791

DESIGN FOR A PENHOLDER

Joseph Lusareta, San Luis Obispo, Calif.

Application March 13, 1939, Serial No. 83,542

Term of patent 3½ years

To all whom it may concern:

Be it known that I, Joseph Lusareta, a citizen of the United States of America, residing at San Luis Obispo, in the county of San Luis Obispo and State of California, have invented a new, original, and ornamental Design for a Penholder, of which the following is a specification, reference being had to the accompanying drawing, forming a part thereof.

Fig. 1 is a perspective view of a penholder, showing my new design; and

Fig. 2 is a front elevation thereof.

I claim:

The ornamental design for a penholder, substantially as shown.

JOSEPH LUSARETA.
